US0D1095279S

(12) **United States Design Patent** (10) Patent No.: **US D1,095,279 S**
(45) Date of Patent: ** Sep. 30, 2025

(54) **TRACKING DEVICE WITH PROTECTIVE CASE**

(71) Applicant: **Shenzhen Tengruifeng IoT Technology Co., Ltd.**, Shenzhen (CN)

(72) Inventor: **Jinzhe Piao**, Jilin (CN)

(**) Term: **15 Years**

(21) Appl. No.: **29/990,354**

(22) Filed: **Feb. 20, 2025**

(51) LOC (15) Cl. **10-04**

(52) U.S. Cl.

USPC **D10/70; D10/104.2**

(58) **Field of Classification Search**

USPC **D10/70, 104.1, 104.2, 121**

See application file for complete search history.

Primary Examiner — George D. Kirschbaum

CLAIM

The ornamental design for a tracking device with protective case, as shown and described.

DESCRIPTION

FIG. 1 is a top, front and right-side perspective view of the tracking device component of the tracking device with protective case according to the present design, shown separately for clarity;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom a bottom plan view thereof; and

FIG. 8 is a bottom, rear, and left-side perspective view thereof.
